UNITED STATES PATENT OFFICE.

EDWARD JAMES DUFF, OF LIVERPOOL, ENGLAND, ASSIGNOR OF ONE-HALF
TO UNITED ALKALI COMPANY, LIMITED, OF LIVERPOOL, ENGLAND.

GAS-FURNACE FOR STEAM-BOILERS.

SPECIFICATION forming part of Letters Patent No. 701,861, dated June 10, 1902.

Application filed July 17, 1901. Serial No. 68,663. (No model.)

To all whom it may concern:

Be it known that I, EDWARD JAMES DUFF, engineer, a subject of the King of Great Britain and Ireland, residing at 30 James street, 5 Liverpool, in the county of Lancaster, England, have invented certain new and useful Improvements in Gas-Furnaces for Steam-Boilers or for other Heating Purposes; and I do hereby declare the following to be a full, 10 clear, and exact description of the invention, such as will enable others skilled in the art to which it appertains to make and use the same.

This invention relates to gas-furnaces, and 15 is especially intended for application to the furnace of steam-boilers; but it can also be employed for furnaces used for other heating purposes.

The said invention has for its object to provide 20 means whereby the gas is very efficiently consumed and the otherwise waste heat utilized.

According to this invention the air to be mixed with the gas for consumption is passed 25 through a passage or passages arranged, as hereinafter described, in proximity to another passage or other passages through which the products of combustion from the furnace pass, the said air then passing into the hereinafter 30 described combustion-chamber through perforations arranged on either side of perforations through which the gas is admitted to the said combustion-chamber, so that the jets of gas issue between and are crossed by jets 35 of heated air, insuring perfect intermingling or mixture of the air and gas, the combustion which takes place being perfected by the baffling actions of perforations through which the gases pass from the combustion-chamber 40 to the boiler or other place where the heat is to be utilized.

The following is a description, with reference to the accompanying drawings, of the arrangement according to this invention as 45 applied to a water-tube boiler, from which its general application to other heating purposes will also be understood.

Figure 1 is a vertical longitudinal section on the line A B C D, Fig. 2. Fig. 3 is a sectional plan, one half on the line E F and the other half on the line G H, Fig. 1. Fig. 3 is a transverse section on the line I J, Fig. 1;

and Fig. 4 is a transverse section on the line K L, Fig. 1.

The gas enters by the gas-flue *a* and valve *b* and passes by the flue *c* to and through the ports *d*, consisting of long narrow slits in the bottom of the combustion-chamber *e*. The said combustion-chamber is made, as shown, of a smaller capacity at bottom than at top, 55 so that the mixture of gas and air expands as it passes upward to the ports *h*' in the roof of the combustion-chamber. As the gas enters the said combustion-chamber through the ports *d* heated air meets it, the said air being 60 directed so that the streams thereof cross the streams of gas from either side, the said air entering by the valve *f* and passing along the narrow central flue *g* and branch flues *g*' *g*'' around the base of the combustion-chamber 7c *e*, into which chamber it passes by the ports *f*' in streams, which meet and cross the gas-streams as aforesaid, so as to thereby insure perfect mixture or intermingling of the air and gas, combustion taking place and the gases 75 passing from upward in the combustion-chamber *e*, expanding as they so pass upward, and then passing through the perforations *h*' in the arched top *h*, which perforations by their baffling effect perfect and complete the intermingling and combustion of the gases, which then pass in contact with the heating-surfaces 80 of the boiler and out by flues *k* *k*' to the chimney. The said flues *k* *k*' are arranged alongside the central narrow air-flue *g*, so as to effect 85 preheating of the incoming air on its way to meet the gas in the combustion-chamber *e*. As shown in Figs. 1 and 3, the flue *g* is of elongated cross-section, with its narrow side 90 in contact with and presenting a limited area to the heating chamber or space containing the boiler or like structure and its wider side in contact with and presenting a larger area to the discharge flue or flues, so that the maximum heat is extracted from the outgoing hot gases to heat the incoming fresh air 95 when the least possible heat is extracted from the heating-chamber. These flues for the escaping products of combustion and the incoming air, respectively, may be increased 100 in number and be arranged alternately, so as to effect a further division of the currents of escaping products of combustion and division of the incoming air-current; but in any case

they are arranged substantially as shown—
viz., so that the air-passages which pass near to
the space containing the boiler (or the equiva-
lent) are narrow and have but a small area
5 presented to the said space containing the
boiler, so as not to deprive the boiler (or the
equivalent) of heat; but the said air-passages
have as much of their area as possible pre-
sented to the escape-flues $k k'$, so as to ab-
10 tract as much as possible of the heat from
the otherwise waste gases leaving the space
containing the boiler—(or the equivalent.)

I claim as my invention—

1. In gas-furnaces, a combustion-chamber
15 having a perforated arch at top and inlet-
ports for gas at bottom and inlet-ports for air
at each side so arranged that the streams of
gas are met and crossed by incoming streams
20 of air proceeding from opposite sides of the
streams of gas, a heating-chamber into which
the hot gases are discharged from said com-
bustion-chamber, discharge flue or flues lead-
ing from said heating-chamber, and an air-
25 flue of elongated cross-section for supplying
fresh air to the air-inlet ports, said flue hav-
ing its narrow side in contact with and pre-
senting a limited area to the heating-cham-
ber and its wider side in contact with and
30 presenting a larger area to the discharge flue
or flues, whereby the maximum heat may be
derived from the hot gases leaving the heat-
ing-chamber through the discharge flue or

flues for preheating the air and the least heat
extracted from the heating-chamber, sub-
stantially as described.

2. In gas-furnaces, a combustion-chamber
small at bottom and having a perforated arch
40 at top, and gas-inlet ports at bottom and in-
let-ports for air at each side so arranged that
the streams of gas are met and crossed by in-
coming streams of air proceeding from oppo-
site sides of the streams of gas, a heating-
45 chamber into which the hot gases are dis-
charged from said combustion-chamber, dis-
charge flue or flues leading from said heating-
chamber, and an air-flue of elongated cross-
section for supplying fresh air to the air-in-
50 let ports, said flue having its narrow side in
contact with and presenting a limited area to
the heating-chamber and its wider side in
contact with and presenting a larger area to
the discharge flue or flues, whereby the maxi-
55 mum heat may be derived from the hot gases
leaving the heating-chamber through the dis-
charge flue or flues for preheating the air and
the least heat extracted from the heating-
chamber, substantially as described.

In testimony whereof I affix my signature
in presence of two witnesses.

EDWARD JAMES DUFF.
